[57] **ABSTRACT**

A right hand margin adjust feature for an automated

typing system for use with cassette tapes and other typing or display systems. This feature enables an automatic typing system of the class described to automatically reformat pre-recorded information according to changed margin settings of a typewriter or printing device or to compensate for words inserted or deleted in previously recorded copy. It is responsive to, and functions to edit, sentence ending punctuation, spaces, tab, hyphens, carrier returns and line returns. Carrier returns and spaces will be added or deleted automatically as dictated by their position in the original copy and by the margin settings. Carrier returns in the original material are deleted and replaced by an appropriate number of spaces until a variable character right hand margin adjust zone is reached. The feature functions at the beginning of the right hand margin zone to analyze and evaluate the remaining characters in the line. The last available interword space in the zone is deleted and replaced with a carrier return if possible. If a word extends through and beyond the variable right hand margin adjust zone, the system will stop, permitting the typist to read by character to the proper position for a hyphen. After the hyphen is typed and the carrier returned the system will continue to read and type in the automatic right hand margin adjust mode. The system will also stop for any previously recorded tab, permitting the typist to insert the tab if it is required or continue to read. Carrier returns at the end of a title, salutations, or a short line, and tabs and hyphens that will always be required may be kept by depressing a "keep" key at the same time as the appropriate character key and thereafter will not be edited by the right hand margin adjust feature.

**RIGHT HAND MARGIN ADJUSTMENT FEATURE
FOR AN AUTOMATED TYPING SYSTEM**

BACKGROUND OF THE INVENTION

The invention is designed to be utilized on an automated typing system which may consist of two functional units: (1) a console which contains two magnetic tape transports, logic, power supply, and operator function keys; and (2) a typewriter which is modified with an electronic keyboard, selected heavy duty parts and additional operator function keys. Such a console is described in part in our co-pending U.S. Pat. application Ser. No. 427,925 filed Dec. 26, 1973 entitled "Search Feature for an Automated Typing System". A typewriter with an electronic keyboard, suitable for use with our invention is described in co-pending U.S. Pat. applications Ser. Nos. 336,240 and 439,310 filed Feb. 27, 1973 and Feb. 4, 1974, entitled "Typewriter with Magnetic Memory" and "A Keyboard for an Automated Typing System", respectively.

It should be understood however that our invention may be modified or adapted for use with many typing systems or justification systems for both automated typing and visual display.

An automated typing system of the class described performs the following operational functions. Information can be printed on hard copy and recorded simultaneously on magnetic tape. Information recorded on magnetic tape can be read and printed out as hard copy. Information recorded on magnetic tape can be duplicated onto a second tape in either a print or a non-print mode. Tape reading, skipping, or duplicating can be stopped automatically on a word, line, paragraph or page and unwanted information recorded on magnetic tape can be skipped over when the tape is being read or duplicated. In addition, information recorded on a magnetic tape may be searched for selected printing or duplicating.

The feature which is the subject of this invention adds an additional function to those described above. By adding and deleting spaces and carrier returns automatically, as dictated by the right hand margin, it enables the automated typing system to reformat pre-recorded information according to changed margin settings of the typewriter or to compensate for words inserted or deleted in previously recorded copy.

In the past the right hand margin of printed copy has been adjusted in primarily two ways. Some systems read a line of prior recorded information, count the number of spaces either in the entire line or in the right margin zone, and then varying the spacing of the interword spaces so that each line reasonably extends to the right margin. Other systems or variations of the immediately above described system type into the right margin zone and perform a carrier return at the first available space or, in one system, at the first syllable break if the operator has previously broken each word into syllables. In those systems which accomplish a carrier return at the last available interword space in the right margin zone, if no spaces are detected in the zone, the printer continues to print characters until the end of the zone. If the operator then wishes to hyphenate the word the operator must extend the typing beyond the right margin.

SUMMARY OF THE INVENTION

The current invention is a highly improved right hand margin adjust feature for an automated typing system which performs editing functions throughout the typed material as well as the right hand margin and is responsive to a number of special characters such as sentence ending punctuation, tabs, hyphens, and line returns in addition to spaces and carrier returns. In addition, the final copy may be typed in either normal style or legal style upon the choice of the operator.

The majority of standard automated type systems continue to type after the bell rings indicating the right margin zone, normally set six characters prior to the right margin. A carrier return is inserted upon the occurrence of a space in the previously typed copy. If no space occurs after the bell rings, the standard typing system fills the six spaces with characters and stops. In other words, if the last six characters consist of the words "I am" the standard automated typing system would carriage return after "I" instead of after "am", the normal carrier return if manually typed. Alternatively, if the last word were "readable", the standard automated typing system would type "readab" and stop rather than "read-" and "able" on the next line.

The device of the instant invention stops at the bell ring, or when the right hand margin zone is entered, and looks at the remaining characters. If two interword spaces are present, a carrier return is inserted and the machine returns on the second space. If no spaces are present, the machine stops so that the secretary can hyphenate at her choosing. Thereafter, pressing a "READ" key only prints one character at a time. Therefore, when the operator reaches a syllable break, the operator can hyphenate the word and return the carrier.

Provision is also made for hyphens or spaces that must be kept regardless of carrier returns such as the hyphens in "second-to-the-last". In order to maintain the hyphens with a standard automated typing system the operator is required to vary the typing pattern such as space, space, character, space, space, which is called a "precedence code". Applicants use a "KEEP" key which, when depressed in conjunction with the appropriate character key, keeps carrier returns, tabs, spaces, and hyphens. This is often used, for example, for carrier returns in the address portion of a letter where only a quarter of a line is normally utilized.

Similarly, if in the body of a letter which is being edited there is a sentence ending punctuation mark followed by a carrier return, the edited version must be punctuated, the carrier return must be eliminated and two spaces must be added after the punctuation mark. A variation, of course, is where an abbreviation occurs, such as "Dr. Smith". In that instance, the keep key would be pressed along with the space after Dr. so that no matter where it occurs there will be the period after Dr., only one space, and then the surname following. Finally, as discussed in the edit sequences described below, the system also functions based on information such as carrier returns or spaces immediately prior to the beginning of the right margin zone, this information being retained in memory units or counters of the device.

To achieve a proper sequence the system operates on an eight phase clock. The earlier phases of the clock are used to enable the edit or adjust function and to de-

tect which characters occur in the right margin zone. The latter phases of the clock are utilized for resolution of the changes in the orginal typed copy which are dictated by the right hand margin adjust feature.

Logical circuitry to accomplish the function of looking forward into the right margin zone comprise a zone insert memory and various flip-flops to indicate the beginning and end of the zone. Alpha numeric characters or other typing characters are analyzed in this system with a special character decoder, which reads data bits in selectric code from a buffer, and a zone recycling counter and a zone shift register memory unit which are combined to detect the occurrence of the editable special characters. Counters and flip flops are utilized to count spaces, carriage returns, line returns and as flags for tabs, sentence ending punctuation or hyphens.

Logical circuitry is then utilized to further evaluate the contents of the zone to determine the existence of the typing pattern prior to and in the right margin zone and to provide a predetermined resolution of the typing pattern in the right margin zone. As indicated above, if a word extends completely across the right margin zone and beyond the right margin, or upon special occurrences such as tabs or underlining, because these are unique to each document and cannot be automatically edited, this invention detects such as occurrence and automatically stops the system prior to proceeding further. Thereafter, the operator may choose the appropriate action and after initiating a carrier return the automated typing system with a right hand margin adjust feature will continue to perform in an automatic mode.

After analysis of the right hand margin zone the system functions to generate or delete spaces and/or carriage returns as required by the analysis and on succeeding phases of the eight phase clock initiates the typing system to edit the copy and record the revised copy, if desired by the operator. With this feature the finished copy can be typed and recorded in either normal form such as used on business letters or in legal form such as used on agreements or briefs or the like.

DESCRIPTION OF THE DRAWINGS

FIG. 1 is a schematic diagram showing the electronic elements utilized in our invention for the detection of special selected characters;

FIG. 2 is a schematic diagram showing the electronic elements utilized in our invention for control of the special characters detected by the circuitry in FIG. 1; and

FIG. 3 is a flow chart showing the essential decision making steps of our right hand margin adjust feature to implement our invention.

DESCRIPTION OF THE PREFERRED EMBODIMENT

A primary function of the right hand margin adjust feature is to relocate spaces and carrier returns when the margins of a previously typed and recorded document have been changed or where an insertion or a deletion has been made to previously typed and recorded copy. To accomplish this function carrier returns in the initially typed copy must be deleted and replaced with one interword space or two interword spaces depending on the immediately preceding occurrence of sentence ending punctuation or not. Carrier returns which occur after sentence ending punctuation, such as a period, a question mark, a colon, or an exclamation mark must be deleted and replaced with two interword spaces. Carrier returns which would occur between two words in a sentence or after non-sentence ending punctuation such as a comma or semicolon must be deleted and replaced with one space.

Since tabs on a typing system will not be set to accommodate the reformed or changed copy the automated typing system stops after the occurrence of a tab in order to allow the operator to position tabular columns as desired. In addition, since the format for a legal document employs additional carrier returns, as compared to normal typing, the subject invention is adapted to produce a legal format from a rough draft copy which is typed in normal style.

To accomplish these functions, provision is made by this invention to alter the following sequences which normally occur in originally typed and recorded information. The copy is reformed in the manner indicated which is suitable for either a normal typing style or a legal typing style. In the following tables a minus sign indicates that the typing function has been deleted and a plus sign indicates that the typing function has been added.

Similar adjustments must be made prior to the right hand margin for sentence ending punctuation, spaces, carrier returns, and tabs to assure that the reformed copy follows the paragraph format of the original and so that an appropriate number of carrier returns will be added in or near the right hand margin. Accordingly, a right hand margin zone is preselected to be a multiple number of characters, for example six characters, and typewriter commands immediately preceding the right hand margin are detected and electronically evaluated to correctly reformat the final typed copy.

15 Accordingly, the present invention includes provisions to make the following changes for either normal typing style or legal typing style when the sequence of commands is as listed below. In the listings below the slash mark indicates the beginning of the "hot zone" or 20 six character zone prior to the right hand margin. In the sequences listed the hot zone is designated zone one. Zones two, three and four are typing sequences where a relevant data command is located one character prior to the hot zone, two characters prior to the hot zone or 25 three characters prior to the hot zone, respectively.

The above exemplary sequences indicate the variations which occur where only punctuation, spaces, carrier returns or tabs are located in the body of the typed material or in the zone prior to the right hand margin. In addition, the invention has provisions to vary both the body and the right hand zone upon the occurrence of line returns, where the carrier is returned to the beginning of a line without starting a new line, and hyphens, which occur either at a syllable break or as part of a standard hyphenated word.

As explained more fully below, carrier returns will occur in the right hand margin at the last available space which occurs therein. A KEEP key is also provided which may be depressed for unalterable typing commands such as hyphenated words like second-to-the-last.

An embodiment suitable to accomplish the functions

and objectives of our invention is shown schematically in FIGS. 1 and 2. The function of the elements in FIG. 1 are primarily to detect and decode the special characters which are controlled by the right hand margin adjust feature and to record the occurrence of sentence ending punctuation and hyphens. Space control is also provided with a two stage space counter. In addition, the elements shown in FIG. 1 provide the logical circuitry to look ahead into the hot zone to determine the occurrence of spaces, the number of which are maintained in the space counter, and other typed characters or special characters indicated by the special character decoder. Finally, the elements of FIG. 1 establish an multiple phase clock in this embodiment having eight phases, for controlling the logical sequence of events in a proper order. Generally, the first and third phases of the eight phase clock are utilized to check for occur-

rence of characters while the latter stages of the clock, the fifth, sixth and seventh phases, are utilized to modify the information in accordance with the objectives of the invention.

The right hand margin adjust system is enabled with an edit enable flop 12 shown on FIG. 2 which is an alternate action flop receiving an inverted differentiated pulse from an edit switch (not shown) on line 14 through a differentiator R1, R2, R4, C8 and C9, and an inverter 15 to the clock input pin 6, of the edit enable flop 12. The occurrence of a master clear signal when power to the unit is turned on resets the edit enable flip flop 12. The master clear is fed to the reset pin, pin 8 of the flip flop 12 along line 17. When the edit switch is depressed the low output on output pin 10 of the edit enable flop 12 is utilized along line 18 through inverter 21 and line 22 to energize an edit indicator light on the console (not shown). The low output on pin 10 of the edit enable flop 12 is also connected to a negative input NAND gate 24, pin 8, the output of which on pin 10, is fed along lines 26 and 27 to reset a print character flip flop 30 and along lines 26, 27, 28, 30 and 31 respectively to reset a carriage return flip flop 33 and the zone inhibit flip flop 34 discussed below. It is also connected with lines 26, 27, 36, 37 and 38 to input pins 1 and 10, respectively, of a hold for delete flop 40 and sets a hold for insert flop 41. Finally, the output of the inhibit NAND gate 26 is connected with lines 26, 27, 43, inverter 45, lines 47 and 48 to input line 50 of FIG. 1, is inverted with inverter 52 and fed along lines 54 and 56 to partially enable NAND gate 58 the output of which, on pin 12, is fed with line 60 to reset a decade counter 62, discussed below. The output of inverter 52 is also fed along lines 54, 64, 67, 68, 70, 71 and 72 where it is utilized to reset the first flip flop 74 of a two stage space counter, a hyphen flag 76, and a punctuation flag 78.

Referring again to FIG. 2, the second input to the NAND gate 24, on pin 9, is utilized to disable or inhibit the margin adjust circuitry in the even pretyped material is duplicated or skipped or if the automated typing system is operating in a record mode but is not reading tape. This prevents the system from attempting to edit information as it is being typed.

These inhibits are accomplished with input lines 81 and 82, the signals on which indicate that the automated typing system is in the duplicate or skip mode of operation. These signals are channelled through a NOR gate 83 along line 85 to input pin 4 of a negative input NOR gate 87. The fact that the system is recording but not reading a tape is detected on lines 89 and 90 which are connected to input pins 4 and 5 of a NAND gate 92, the output of which, on pin 6, is connected with line 94 to the input pin 5 of the negative input NOR gate 87.

In addition, the right hand margin adjust system is also inhibited during, and reset after, execution of a carrier return by the typing system.

This is accomplished with NAND gate 96 which is connected to input pin 3 of the negative input NOR gate 87 with line 98. One input to NAND gate 96 is the read indicator, indicating that the system is reading a tape, which is connected to input pin 2 of the NAND gate 96. Another input, on pin 1, indicates that at least one carrier return is loaded in a carrier return shift register 100 and that the carrier return flip flop 33 has been set, thereby causing the typing system to execute the carrier return.

The fact that at least one carrier returns is loaded is indicated by a high signal on the first stage of the carrier return shift register 100, pin 15. This is connected with lines 103, 104, 105 and 106 to a NAND gate 107.

5 The enabling signal to the typing system is indicated by a high output from the carrier return flip flop 33, pin 15. This is connected with lines 109, 110 and 111 to the second input of the NAND gate 107. The low output of the NAND gate 107 when both conditions are met 10 is connected with line 114 to input pin 1 of the reset NAND gate 96.

As explained more fully below the system sequence of operation is controlled by the eight phase clock. Therefore, the third signal, which fully enables the 15 reset NAND gate 96 is phase one of the clock, thus assuring that the system parameters are not reset until after the carrier return has been executed. Phase 1 of the clock is connected with lines 116 and 117 to input pin 13 of the NAND gate 96. The output of NOR gate 20 87 is connected with line 120 to input pin 9 of NAND gate 24.

Therefore, when the system is initially energized, and after carrier returns are accomplished during the right hand margin adjust feature, all system control units are 25 set or reset to initiate editing of the next line.

Referring now to FIG. 1, a special character decoder 122 is provided which decodes in a suitable manner the occurrence of a sentence ending punctuation, such as a period, question mark or a colon, a tab, a carrier return, a space, a hyphen, or a line return on output pins 1-6, respectively. These signals are decoded from a read buffer (not shown) which contains the selectric code positions assigned each character. In addition, a signal indicating that an alphanumeric character, such as a letter of the alphabet, is in the buffer also originates from the read buffer, in the instant embodiment from the seventh read buffer position.

As data changes in the read buffer extraneous noise pulses will occur on the input lines to the special character decoder 122 as the data bits are changing. Therefore, the buffer cannot be read until after the signals have settled. In addition, to implement the decision making processes, as indicated on the flow chart in FIG. 3, each successive character or function in the 40 read buffer must be sequentially detected, decoded and the proper functions must be generated in accordance with or similar to the exemplary sequence tables set forth above. Accordingly, an eight phase clock is utilized shown in FIG. 1 particularly, FIGS. 1c and 1d.

50 Basically, after a rest period during the zero phase of the clock, the first and third phases are used to detect characters and to initiate the function generating processes. The fifth, sixth and seventh phases of the clock are utilized to generate the appropriate function in accordance with the character or typing command which was detected in view of previously recorded information contained in the flip flops, counters and shift registers of the circuitry. The remaining phases of the clock are utilized as rest periods to assure sequential operation. In addition, the flops utilized are edge triggered devices wherein a flop may be conditioned on the leading edge of a clocking signal with the action of the flop taking place on the trailing edge of the clocking signal.

55 60 65 66 The multiple phase clock utilized is basically a decade binary counter 62 with a binary to decimal decoder 130 on the output. This provides eight stages, phases zero through seven. The D input on pin 12 of

the binary to decimal converter 130 is utilized as a disable so that there are eight available clock phases out. Phases one, three, five, six and seven are utilized as explained above to control the sequence of the right hand margin adjust circuitry. These are the actual active states. Phase zero and phase two are utilized as a rest or neutral stage and phase four is used only as a stopping position while getting more tape to read additional information into the buffer (not shown):

Nine hundred and sixty kilohertz on input line 132 is utilized as the base clock frequency so each clock pulse is approximately 500 nanoseconds wide. The 900 and 60 kilohertz is fed into the counter from input line 132 line 134 through NAND gate 135 negative input NAND gate 137 lines 138 and 139 negative input NAND gate 141 to input pin 1 of the counter along line 143. The nine hundred and sixty kilohertz is also connected from negative input NAND gate 137 along lines 138 and 145 to the D input of the binary to decimal decoder 130, input pin 12, to modulate the clock pulses by shifting them to the non-existent second output. Accordingly, each clock pulse has a pulse width of approximately five hundred nanoseconds.

A disabling signal is also connected to NAND gate 135, input pin 5, which is a data strobe from the typing system keyboard circuitry which inhibits the clock until the data command has been printed. A disabling signal to control the clock is also connected to input NAND gate 37 which originates from the circuitry in FIG. 2 and is connected from input line 147 to negative input NAND gate 150. This is also sequenced with phase four of the clock, being connected from output pin 5 of the binary to decimal decoder 130 along line 153 to input pin 11 of negative input NAND gate 150. The output of negative input NAND gate 150 is connected from output pin 13 with line 151 to input pin 13 of negative input NAND gate 137.

As the counter 62 counts to decimal eight output A, on output pin 12 will go high. This is connected to input pin 9 of NAND gate 141 along lines 155 and 156 and to input pin 1 of NAND gate 158 along lines 155 and 160. If a low going signal, to be discussed below designated edit run, is present on input line 163 output pin 6 of a negative input NOR gate 164 will be high which will fully enable NAND gate 153 causing output pin 3 of NAND gate 153 to go low. This is connected to NAND gate 58, pin 2 with line 166. Therefore, output pin 12 of NAND gate 166 will go high which will reset the counter along line 160 which will pull the A output of the decade counter 62, pin 12, low. Along the circuitry traced immediately above the reset signal will go low and the counter 62 will automatically start again. Therefore, if the edit run signal is low the counter 62 will run continuously.

An edit clock signal on input line 169 is connected to pin 3 of negative input NOR gate 164. This is a clock signal from the printer (not shown) indicating that the printer is not ready to accept additional data. This will stop the counter at stage 8 where the A output of the counter 62, on pin 12, is high and the counter 62 will rest because input pin 2 of NAND gate 158 will be high. Therefore, pin 2 of NAND gate 58 will be low. Thereafter, when pin 2 of NAND gate 58 goes high, the counter 62 will be reset and operation of the clock will continue as described above.

The high output on stage A of the counter 62, on output pin 12, is also used to inhibit clock pulses to the

counter 62 with lines 155 and 156 connected to input pin 9 of negative input NAND gate 141. The second input to NAND gate 141, as described above, is the 960 kilohertz signal utilized as the base clock frequency.

5 The additional enabling signals on NAND gate 58 are a signal to cycle data and the edit signal. The edit signal on input line 50 is inverted with inverter 52 and connected with lines 54 and 56 to input pin 13. The signal which stops the clock while data is being recirculated 10 originates from a recirculate control flip flop 171, output pin 15, and is connected with lines 173, 174 and 175 to input pin 1 of NAND gate 58.

In the manner described, the eight phase clock is established and controlled by the edit clock, edit run and 15 edit control signals on input lines 169, 163 and 147, respectively. The low going clock pulses from output pins 2, 4, 6, 7 and 9 are inverted with inverters 178, 179, 180, 181 and 182 and utilized as sequence controls designated Phases one, three, five, six and seven on output 20 lines 185, 186, 187, 188 and 189.

As indicated in the first table of sequences listed above the carrier returns which occur between two words in the body of the document that is being reproduced will be deleted and a space will be inserted in 25 place of the carrier return. If the carrier return detected follows sentence ending punctuation the carrier return will be deleted and two spaces will be added. If a hyphen occurs, and there is no indication that the hyphen is to be kept, the hyphen will be deleted and no 30 space will be inserted in place of the hyphen. If a hyphen is detected that is to be kept following a carrier return, the hyphen will be kept and no space will be inserted in place of the carrier return. If a tab is detected in the typed material the typing system will automatically stop so that the operator can position tabular columns in the new format as she chooses. This is accomplished in the following manner.

Space command signals are generated on output line 194 in response to the punctuation flag flop 78 and the 40 space counter comprised of two flops 74 and 196. These are connected to a negative input NOR gate 198 along line 200 from the punctuation flag 78 and 201 from the space counter flop 74. A signal indicating sentence ending punctuation from the special character 45 decoder 122 is fed along line 204 through NOR gate 205 to condition the punctuation flag 78 at input pin 4 which is clocked by phase five of the eight phase clock along lines 206 and 207 to input pin 12 of the punctuation flag 78. As the output on pin 3 of the flop 78 goes high this partially enables NAND gate 210, the low output from which on pin 11 is fed along line 200 to negative input NOR gate 194 to generate a space command. The second enable on NAND gate 210, pin 13 is connected to pin 14 of the second stage 196 of the space 55 counter. When pin 14 of the second stage 194 of the space counter is cleared high, as is discussed below, the high signal on pin 14 will fully enable NAND gate 210 and a space command will generate a space.

When a space or spaces are inserted to replace a carrier return or the like this produces a low going signal 60 on input line 213 which is connected through negative input NOR gate 215, pin 5, and from the output, pin 6, of negative input NOR gate 215 along lines 217, 218 and 219 to input pins 9 and 4 respectively of the space counter flip flops 74 and 186. The first time the space counter 15 clocked, on input pins 6 and 1 of the flip flops 74 and 186, respectively, by phase six of the eight

phase clock, along lines 222 and 223 through inverter 181 and along lines 226, 227, 228 and 229 respectively, pin 11 of the first flop 74 will be low which holds the reset pin, pin 3, connected from output pin 11 of the first flop 74 along line 231 to the second flop 196, low. This holds the second flop 196 in a reset condition regardless of the occurrence of the clock pulse on clock input, pin 1.

Therefore, the first time that the clock pulse occurs one space is counted and a second space must be generated to clock output pin 14 of the second stage 196 of the space counter low. This removes the enable from NAND gate 210 on pin 13 to stop generating spaces through negative input NOR gate 198. Accordingly, two spaces are generated to replace a carrier return after the punctuation flag 78 has been set.

If the signal on NAND gate 210, pin 12, from output pin 3 of the punctuation flag 78 is low, indicating that there was no punctuation, but a carrier return was detected by the special character decoder 122. This must be replaced by only one space. Accordingly, the output of the first flip flop 74 of the two stage space counter is connected from output pin 11 along lines 231 and 201 to input pin 1 of the negative input NOR gate 198. After the first space is generated on line 213 the output on pin 11 of the first flip flop 74 will go high, this signal being connected to input pin 1 of the negative input NOR gate to shut off the space command to stop generating spaces. The existence of the carrier return originates from the special character decoder 122 on line 234, is fed to the circuitry of FIG. 2 along line 237 and is used to condition pin 1 of the punctuation flag 78 from the special character decoder 122 along lines 234, 238, negative input NOR gate 241, lines 244 and 245 to pin 3 of negative input NAND gate 247 and to the second enabling input of NAND gate 247, input pin 2, from line 244 through NOR gate 205 and line 251. Since both of the inputs to negative input NAND gate 247 are then low the high output will condition the punctuation flag 78 to effectuate the space commands as described above. The carrier return signal, if detected in the hot zone prior to the right margin is also connected with lines 234, 253, 254, negative input NOR gate 258, and line 260 to NAND gate 262 and line 263 to input pin 11 of a zone insert memory 270 to clock the memory 270 for reasons which will be described more fully below.

If a hyphen is detected in the typed copy this would indicate that a word has been hyphenated at the end of a line unless the keep key (not shown) is depressed along with the hyphen, for example, prehyphenated text. When the hyphen is indicated by the special character decoder 122 on output line 272 it is connected with line 273 to negative input NAND gate 275, the high output of which pin 10, is inverted with inverter 277 and is used to direct set the first stage 74 of the space counter, input pin 7, to indicate one space. Since, however, no space is generated, no space will occur in the retyped copy. In other words, the reason for direct setting the space counter is to avoid generating a space command to replace a carrier return in hyphenated text at the end of a sentence. It should be noted that the second enabling signal, on input pin 8, of negative input NAND gate 275 is the phase seven clock pulse. As explained above, the various phases of the clock are utilized to clock in the special characters because as data shifts into the read buffer extraneous pulses may ap-

pear as the data changes. By the time the phase seven clock pulse is emitted the read buffer data bits are settled and may be accurately decoded by the special character decoder 122. The system functions as described above until the right hand margin zone is reached. The start of the zone is manually set by the operator of the typing system when the right hand margin is set. When the zone switch makes, indicating that the carrier has reached the beginning of the zone, this produces a low going signal on input line 280 to set and condition a start zone flip flop 282 along lines 280, 284, NOR gate 285 and line 286 to input pin 4 of the flip flop 282 to set it and along lines 280 and 288 to input pin 2 of the flip flop to condition it. Thereafter, the next six characters in the read buffer (not shown) will be individually interrogated to reformat the right hand margin. The number of characters to be interrogated might be varied, as explained more fully below. In the six character zone the circuitry functions as follows.

If a carrier return is detected it is utilized as the carrier return in the right hand zone. If one or more spaces are detected in the hot zone the last available interword space is deleted and replaced by a carrier return. If a kept hyphen is detected the hyphen is kept and a carrier return is inserted after the hyphen. If no spaces or carrier returns are detected in the zone the system automatically stops so that the operator, by depressing the read switch (not shown), can sequentially print one character at a time to determine where a hyphen should be inserted at an appropriate syllable break. After the carrier return is executed the automated typing system will again operate in the right hand margin adjust mode and will continue to delete carrier returns in the body of the information and insert them in the zone immediately preceding the right hand margin.

Before the zone is reached if two carrier returns are detected in the normal mode, or three in the legal mode, indicating a new paragraph, these carrier returns are kept no matter where they occur in the body of the text.

The signal indicating that the hot zone has been reached conditions and sets the start zone flop 282 as explained above. The low signal on output pin 5 of the start zone flip flop 282 is differentiated with C8, R1 and R2 and connected with line 291 to input pin 9 of a negative input NAND gate 294. The second enable, on input pin 8 of the negative input NAND gate 294, if low indicates that a carrier return is loaded into the carrier return counter indicating that immediately preceding the zone a carrier return was detected. This is connected from input line 297 and line 298 to input pin 8 of the NAND gate 294. The carrier return loaded signal originates from the circuitry shown in FIG. 2, output line 300, which will be discussed below. If a carrier return is loaded the sequential checking of the characters in the zone will not occur. The carrier will simply be returned upon the occurrence of the zone switch.

The output of negative input NAND gate 294 is connected with line 303 to input pin 12 of a second NAND gate 305. Similarly, the second enabling input to NAND gate 305 is connected to input line 307 which indicates that immediately preceding the zone there was no indication that a carrier return should be generated. Again, in the event the prezone circuitry has indicated that a carrier return should be generated the carrier return will be effected immediately upon reaching the zone.

The output of NAND gate 305, on pin 11, is connected to an end zone flip flop 310 and a buffer recycling control flip flop with lines 312 and 313 and line 315 to input pins 8 and 3 thereof, respectively. The output on the second flip flop 171, on pin 15, is connected with lines 173, 174, 318, 319 and 320 to enable a three stage 325, 326, 327 zone recycling counter on input pins 2 and 3 of each of the stages 325, 326 and 327 of the counter. Pin 1 of the first stage of the first counter 325 is connected with line 330 to the 960 kilohertz signal which runs the clock. The direct connection is made because the clock is deactivated for certain conditions and is in a deactivated state upon the initiation of the zone. The 960 kilohertz is divided by four in the B and C stages of the first counter 325. The B stage which is coupled automatically to the C stage and C stage output, on pin 8 of counter 325, is connected to input pin 9 of NAND gate 333 with line 335. The output of NAND gate 333, on output pin 8, is connected to the read buffer (not shown) which clocks the read buffer forward. The output of the first counter 325 is also connected with line 338 to the input of decade counter 326, on input pin 14. The output of the first decade counter 326, on pin 11, is connected to the second decade counter 327 input on pin 14 and the output on pin 11 of the second decade counter 327, which is now divided by 100, is connected with line 340 to the first stage of the first counter 325 on pin 14 which yields a clock pulse output on the output of stage A of the first counter 325 on output pin 12. Consequently, the output on pin 12 will go high at 100 and low at 200. The low going signal is utilized as a clock pulse for the recirculate control flip flop 171 being connected to input pin 1 thereof with line 344. This stops the clock and recirculates, with associated circuitry (not shown), the two hundred characters or typewriter functions into and through the read buffer.

The first six characters of the two hundred characters which are recirculated are those characters which are interrogated to determine the contents of the zone, particularly carrier returns and spaces, so that a carrier return may be executed or inserted as required. This is accomplished as follows.

The output of the end of zone flip flop 310, on output pin 10, is connected with line 346 to a shift register 270, designated zone insert memory, input pin 10. This enables the counter 270 to clock available spaces in, by shifting the shift register right each time a space is detected on the clock input, pin 11, as long as the output of the end of zone flip flop 310 is high. After the first four counts pin 8 of the first decade counter 326 goes high which is connected to the J input, input pin 9 of the J K end of zone flip flop 310 with line 348. Therefore, the next time that the clocking pulse goes low on the end of zone flip flop 310 the counting will stop and the flip flop 310 will be clocked off. This occurs when the output of the first decade counter 326 of the zone recycling counter on output pin 12 goes low which is at a count of six. This yields the six characters which are detected and decoded by the special character decoder 122 to determine the action to be taken in the right hand margin hot zone.

The buffer will continue to recirculate to the count of 200 so that after the checking has been accomplished the characters in the read buffer will be at precisely the same position that they were prior to the check of the characters in the hot zone.

Checking in the hot zone is further accomplished with NAND gates 350 and 262 and two NOR gates 258 and 352 which are utilized to detect the occurrence of spaces or carrier returns in the hot zone. The occurrence of spaces is detected on line 354 and fed through negative input NOR gate 215, lines 217 and 356 to input pin 1 of NAND gate 350. Generated spaces are detected from the generated space input line 213 through NOR gate 215 to the same input pin of the NAND gate 350. The second enabling input to that NAND gate 350 is connected to the key-board keep signal on input line 358 along lines 359 and 360. The absence of a signal indicating that the space should be kept fully enables NAND gate 350, the output of which is fed along line 362 to input pin 4 of the negative input NOR gate 258. The output of NOR gate 258 is fed along line 260 to input pin 9 of NAND gate 262 which partially enables that NAND gate 262.

Occurrence of a carrier return is detected on output line 234 of the special character decoder 122 and is fed along lines 253 and 254 to the second input pin, pin 3 of the negative input NOR gate 258 and hence to the NAND gate 262. The second enable on the NAND gate 262, on input pin 10, is the phase six clock pulse utilized for control as discussed above. In addition, a second input to NOR gate 352 on input pin 12 is the initial signal to the clock discussed above. This signal from output pin 8 of NAND gate 333 is fed along lines 364 and 366 to input pin 12 of the NOR gate 258. Therefore, the NAND gate 262 is enabled when the six characters are being read and the occurrence of a carrier return or a space or a generated space will clock the zone insert memory counter 220 to indicate that one or more spaces or carrier returns have been located in the hot zone. This indication, on output pin 3, of the zone insert memory counter 270 is connected to output line 368 and utilized as described below primarily to generate carrier returns in place of spaces or, in the event a carrier return occurs within the zone, to utilize that carrier return to begin the new line.

If the signal on output 3 of the zone insert memory counter 368 is one or more the sequence continues to reformat the hot zone. If the output of pin 3 is zero, indicating that no special character was encountered, this indication is connected to a zone stop flip flop 370 along line 372 to the D input, pin 12, of the stop zone flip flop 370. After the read buffer has been recirculated the full 200 characters pin 15 of the recirculate control flip flop 171 goes high which is connected to the clock of the zone stop flip flop 370 by lines 173, 174, 368, 319, and 374, to input pin 11. The output of the zone stop flip flop 370 serves to stop the automatic operation of the system and thereafter the operator must determine where the line will end, hyphenate and perform a carrier return to reinitiate operation of the system. The circuitry automatically puts the system into a read by character mode which means that every time the operator depresses the read switch (not shown), the system will read and print one character at a time. The operator may then insert a hyphen or a carrier return or multiple carrier returns. Once a carrier return has been accomplished and the operator depresses the read switch again, the right hand margin adjust feature circuitry will be enabled in the manner described above and the system will automatically continue in the automatic mode without further operator action.

As indicated above, six characters were chosen as an exemplary feature for the right hand margin zone. In fact, the multiple character hot zone could be chosen to be any number of characters depending upon the choice of design. Six, nine or twelve characters may be easily accomplished in the preferred embodiment with no changes in parameters and relatively minor changes in connections. Currently the preferred embodiment as described would be limited to a maximum zone of 200 characters, that being the extent of the read buffer. However, additional buffer stages may be added to increase the potential of the circuitry as desired.

To vary the extent of the zone within the 200 character limitation by the read buffer all that would be necessary would be to change the controlling pins that are going into the J, clock and K inputs, pins 9, 6 and 12 respectively of the end zone flip flop 310. With additional gating any number between 1 and 200 may be utilized as the extent of the right hand zone.

In the event the zone insert memory counter 368 has detected special characters in the chosen right hand margin hot zone the high output on pin 3 will prevent the zone stop flip flop 270 from terminating the automatic sequence of operation. The high output on the recirculation control flip flop 171, pin 15 is connected with lines 173, 380 and 382 to the shift left input of the zone insert memory counter 270, on input pin 10. Thereafter data bits are shifted out of the zone insert memory counter 270 every time a space or carrier return is detected by the special character decoder 122. Note that this also occurs on phase 6 of the eight phase clock through negative input NOR gate 352 which fully enables NAND gate 262 when spaces or carrier returns are detected in the manner described above.

The last interword space is converted to a carrier return when the signal on pin 3 of the zone insert memory 270 goes low indicating the last space has been reached. A carrier return is generated by the circuitry shown in FIG. 2 as described more fully below. As a carrier return is generated, the signal on input line 307 goes high which enables NAND gate 305 through input pin 13. The low output on pin 11 clears the end of zone flip flop 310 and the recirculate control flip flop 171 and the output from pin 15 of the recirculate control flip flop 171 resets the zone recycling counter 325, 326, 327 and the decade counter 62 for the clock from output pin 15 along lines 173, 174, 318, 319 and 320 and line 175 NAND gate 58, line 60 to the clock counter 62, respectively.

Since a carrier return in the hot zone will initiate a carrier return on the reformed copy the zone insert memory counter 270 is primarily utilized to count spaces in the zone in order that the last space in the zone is utilized for the carrier return. The output of the zone insert memory 270 is connected from output line 368 on FIG. 1 to input line 400 on FIG. 2. The original high output of the greater or equal to one input 400 on FIG. 2 indicates that the system is operating in the zone. As indicated above, when that input 400 to the circuitry on FIG. 2 goes low it indicates that the last space has been reached and thus one or more carrier returns must be inserted to properly reformat the typed copy.

Referring now to FIG. 2, insertion of carrier returns in place of spaces or the like are accomplished primarily with a carrier return shift register 100. Provision is made for the operator to select whether or not the in-

formation will be typed in a reformed style in legal form, which double spaces each line. Therefore, when a legal switch (not shown) connected to input line 402 is energized, it will load two carrier returns to replace the last interword space located in the zone. If the operator selects the normal mode of operation only one carrier return is loaded to replace an interword space.

Carrier returns are inserted or executed after the contents of the zone have been determined. If the signal on line 400 from the zone insert memory shift register 270 is low, no carrier returns or spaces were detected in the zone and the system will be stopped for operator action. If the signal on line 400 is high one or more carrier returns or spaces were detected in the zone. Carrier returns detected in the zone will be utilized and executed. The last interword space will be utilized and a carrier return inserted if no carrier returns were detected.

Carrier returns detected by the special character decoder 122 are connected from output line 237 in FIG. 1 to input line 410 on FIG. 2. The existence of an alphanumeric character or depression of the keep key are detected on input lines 358 and 412 of FIG. 1 and are connected with lines 359, inverter 414, lines 415 and 416 and line 418 respectively to a NOR gate 421, the output of which on line 423 is connected to input line 425 of FIG. 2. Therefore, if neither a carrier return nor an alphanumeric character nor a kept character of any kind is detected the output of NOR gate 428 will be high which conditions the print character flip flop 30 on input pin 16 along line 486. As shown the phase seven clock pulse clocks the flop 30.

The high output on pin 15 of the flop partially enables NAND gate 488, along line 490, which is fully enabled when the greater or equal to one signal on line 400 goes low indicating that the last space has been reached.

When the greater or equal to one signal goes low it is inverted with inverter 492 and the high output on pin 10 of the inverter 492 is connected with lines 493 and 494 to input pin 10 of the NAND 488 gate. The low output on pin 8 of NAND gate 488 is connected with line 496 to input pin 8 of negative input NAND gate 430.

The second enabling input to NAND gate 430 on input pin 9 is connected to line 486 which indicates that neither a character return or a kept character was detected. Therefore, output pin 10 of the negative input NAND gate 430 will be high. This is connected with lines 497, 498 and 499 to input pin 3 of an inverter 502 and with line 504 to input pin 6 to a negative input NAND gate 506. The output of the inverter 502 is connected to a capacitor C10 and with lines 508 and 509 to input pin 5 of the NAND gate 506. This differentiator creates a short positive pulse from the output, on pin 4, of NAND gate 506. This is connected with line 508 to input pin 13 of NAND gate 432.

The second enabling input to a NAND gate 432 is connected with line 435 to the carrier return input line 410 and since no carrier return was detected NAND gate 432 is fully enabled so that the output, on pin 11, will go low with a short pulse. This is connected with lines 512 and 513 to input pin 4 of a negative input NOR gate 520, the output of which, on pin 6, is connected with line 524 to input pin 9, the SO input of the carrier return shift register, 100.

The output of NAND gate 432, on pin 11, is also connected with lines 512, 526 and 527 to an inverter 530, the output of which is connected with line 531 to input pin 12 of NOR gate 533. The low going pulse on the output thereof is connected with line 535 to an inverter 536 which yields a high going pulse on the S1 input, pin 10, of the carrier return shift register 100. At the same time as the inverter 530 output, on pin 12, goes high it gives a differentiated pulse to the input, pin 8 of a NOR gate 538, the low going output of which is connected with lines 540 and 541 to the clock input of the carrier return shift register 100 on pin 11. As explained above, this loads one carrier return into the shift register 100, indicated on the QA output, if the system is set by the operator to the normal typing style or two carrier returns, into the shift register 100, indicated on the QA and QB outputs, if the operator has chosen the legal form.

Finally when the differentiated pulse from NAND gate 432 goes low, on pin 11, this is connected with lines 512, 526 and 544 to input pin 12 of a negative input NOR gate 545 which is inverted with inverter 547 and the low pulse from output pin 6 of inverter 547 is connected with lines 548 to direct set the carrier return enable flip flop 33 on input pin 2.

The resulting high output on pin 15 of the carrier return enable flip flop 33 is connected with lines 109, 110 and 111 to partially enable NAND gate 107. NAND gate 107 is fully enabled by the QA output of the carrier return shift register 100 and is connected thereto with lines 103, 104, 105 and 106.

The output of NAND gate 107 is connected with lines 114 and 487 to inverter 489, the output of which partially enables NAND gate 550. The second enabling input to NAND gate 550 is the phase six clock pulse connected in input pin 2 from input line 552 along lines 554 and 555.

The output of NAND gate 550 is connected to output line 557 designated "carrier return insert" which inserts the carrier return to initiate the new line of copy.

The direct set of the carrier return enable flip flop 33 is also used upon the occurrence of an end of page code on input line 560, which indicates that the document being reproduced has been completed. This input is connected to input pin 10 of a three input NAND gate 563 through a negative input NOR gate 561 with line 562. The enabling input to the NAND gate 563 on pin 9 is the phase 5 clock pulse which is connected to input pin line 470 and fed through a NOR gate 565, inverter 567 and lines 568 and 569 to input pin 9. Phase three of the clock is also connected to NOR gate 565 along lines 571 and 572. The output of NAND gate 563, pin 8 is connected with line 575 to input pin 13 of negative input NOR gate 545 to direct set the carrier return enable flip flop 33 as discussed above. Therefore, if carrier returns are stored in the carrier return counter 100, one for normal, or two in the case of legal form, this causes the system to execute the carrier returns before the system is de-energized when an end of page code or the like is received.

The second input to negative input NOR gate 561 on input pin 2, originates from NAND gate 576, output pin 12, and is connected to negative input NOR gate 576 along line 578. The three inputs to NAND gate 576 are designated "column 3", on input pin 13, "read buffer 1", on input pin 1 and "read buffer 2" which is inverted with inverter 580 and connected to input pin

2 of NAND gate 576. If these signals enable NAND gate 576 it also sets the carrier return enable flip flop 33 to cause execution of any carrier returns in the carrier return counter 100 prior to stopping the system from operating. If each of these signals is present it indicates that the tape in the tape cassettes is being rewound to go to the beginning. Therefore the operator no longer wishes the edit to function. It is one indication of the cessation of operation.

Similarly, if a stop code is present on input line 582 which is connected to NAND gate 585 and no recognition code, indicating the beginning or end of a recorded line of copy, is present in input line 584, the absence of a recognition code being a high signal, NAND gate 585 will be fully enabled upon the occurrence of phase 3 of the clock connected with input line 571 to input pin 4 of NAND gate 585. This also indicates a cessation of operation due to the stop code and the output on pin 6 of the NAND gate 585 is inverted with NOR gate 464 and connected with line 465 to the clock input of the carrier return flip flop 33. Connection to the clock input pin will convert only stored carrier returns to spaces if the carrier return occurs in the body of the text or will execute any stored carrier returns from the 25 carrier return shift register 100 if in the zone.

The operator's choice as to whether or not the typed form of the finished copy will be in legal or in normal form is determined by depression of a legal switch (not shown). This produces a signal on input line 402 which is connected with line 588 to input pin 3 of a select gate 590. That signal is also inverted with inverter 404 and connected with lines 405 and 592 to input pin 5 of the second integral gate input to select gate 590. As explained above the signal is also connected from inverter 404 with lines 405 and 406 to input pin B of carrier return shift register 100. If the signal on input line 402 is low this indicates that the system is in legal mode of operation; if it is high this indicates that the system is in the normal mode of operation.

The second shift register output of the carrier return shift register 100, designated QB on output pin 14, is connected with line 595 to input pin 2 of the first integral NAND gate of the select gate fed QB on output pin 14, is connected with line 595 to input pin 2 of the first integral NAND gate of the select gate 590. The third register output of the carrier return shift register 100, designated QC on output pin 13, is connected with line 596 to input pin 4 on the second integral NAND gate of select gate 590. Consequently, two carrier returns will be enabled through the first integral NAND gate of select gate 590, output pin 6. And, if the legal switch is depressed, three carrier returns will be enabled from the third output of the carrier return shift register 100 through the second integral NAND gate of select gate 590.

When the correct number of carrier returns are registered the output of select gate 590 will remain low until the carrier returns are executed. The output of select gate 590, pin 6, is connected with line 598 to input pin 9 of negative input NOR gate 600. When the output of negative input NOR gate 600, pin 8, goes high this is connected with line 602 to input pin 4, or the J input, of the carrier return counter flip flop 33. The flip flop is clocked on phase 5 of the clock which is connected, as described above, from input line 457, along line 460 to inverter 462 line 463 NOR gate 464 and line 465 to input pin 1 or the C input of the carrier return counter

flip flop 33. When the carrier return counter flip flop 33 is clocked output pin 15, the Q output, will go high which starts the carrier return sequence.

Clock control will be turned off to prevent further action from taking place while carrier returns are inserted. This is accomplished from output pin 15 along line 109, through NAND gate 605, the output of which on pin 3 is connected with line 606 to input pin 10 of NAND gate 608, the output of which controls the clock on output line 610. The second enable on NAND gate 605, input pin 1, is connected with line 612 to the read indicator input on line 614 and the second enabling input to NAND gate 608, input pin 9, is connected along line 616 to the output of NAND gate 620 which is enabled on phase 1 of the clock along lines 116, 622 and 623 to input pin 13 of the NAND gate 620.

The high output on the carrier return counter flip flop of pin 15 is also connected with lines 109 and 110 to the D input of the zone inhibit flip flop 34 so that the flip flop 34 can be clocked on the trailing edge of the carrier return enable signal from NOR gate 464. Finally the carrier return enable flip flop 33 output on pin 15 is connected along lines 109, 110 and 111 to NAND gate 107, input pin 4, the output of which on pin 6 is connected with lines 114 and 487 to inverter 489. The high output on pin 2 of inverter 489 is connected to NAND gate 550. The second input to NAND gate 550 is connected with lines 552, 554 and 556 to phase 6 of the clock. Therefore the output of NAND gate 550 will go low on phase 6 of the clock for one pulse. This is connected to output line 557 which inserts carrier returns on the tape and in the typed material.

In addition, the output of inverter 489 is connected with line 626 to input pin 11 of NOR gate 533 the output of which is connected with line 535 to inverter 536 which is connected to the S1 input, pin 10, of the carrier return shift register 100.

Therefore every time that a carrier return is inserted the carrier return shift register 100 will shift one left or count one carrier return back. When the shift register 100 counts one carrier return back this will of course take the high signal off the J input of the carrier return counter flip flop 33, input pin 4. However, the K input of pin 16 will still be low and thus the system will not be cleared.

The signal to the K input on pin 16 of the carrier return counter 3E is connected with line 455 to output pin 12 of NOR gate 450. The three inputs to NOR gate 450 are indications that there is at least one carrier return loaded in the carrier return shift register 100, that a carrier return is indicated by the signal on input line 410 or that a tab or carrier return has been recorded in conjunction with the keep key indicating that it should be kept. The carrier return loaded signal originates from the QA output or first register of the carrier return shift register 100 and is connected from output pin 15 along lines 103 and 104 to input pin 13 of NOR gate 450. The carrier return signal is connected along lines 410, 435, 436 and 437 to inverter 440, the output of which is connected with lines 442, 443 and 444 to input pin 2 of NOR gate 350. The third input, on pin 1 originates from NOR gate 628, the inputs to which on pins 5 and 6 are tab and carrier return respectively. The tab input is connected from the input line 630 through inverter 632 and along line 634 to input pin 5 of NOR gate 628. The carrier return indication is connected from the output of inverter 440, discussed immediately

above, along lines 442 and 636 to input pin 6. The output of NOR gate 628, on pin 4, is connected with line 638 to input pin 3 of NAND gate 640. The second input to NAND gate 640, on pin 2, is connected to input line 425, which an alphanumeric character or a keep signal, with lines 470, 471 and 642 to input pin 2.

The combination of the keep signal with the carrier return in addition to being fed through NOR gate 450 to carrier return counter flip flop 33 to prevent it from being cleared is also connected with line 644 to inverter 658, the output of which is connected with line 650 to negative input NOR gate 600, input pin 10. As explained above, the output on pin 8 of negative input NOR gate 600 will set the carrier return enable flip flop 33, on input pin 4 in the event no carrier returns had been earlier detected. Therefore if only one carrier return which is to be kept is detected by the circuitry it is not necessary to have any carrier returns enabled by the flip flop 33, or stored in the carrier return shift register 100 in order to execute carrier returns. The combination of a keep signal in conjunction with the carrier return signal will automatically, in the manner described above, set the carrier return enable flip flop 33 to begin execution of the carrier returns. In addition, since the circuitry has been set, in the event there are carrier returns following the kept carrier return they will automatically be kept due to the presetting of the carrier return enable flip flop 33 and, thus, it is only required to depress the keep key with the first carrier return of a series of carrier returns to, for example, start a new paragraph.

Additional flip flops are provided as shown in FIG. 2, in particular FIG. 2d. Two flip flops are designated "hold for delete" and "hold for insert" and the third flip flop is designated "insert clock control". The hold for insert flip flop 41 and the insert clock control flip flop 654, connected thereto, prevents the system from advancing the read buffer (not shown) while carrier returns, spaces or the like are being inserted. The hold for delete flip flop 40 prevents the system for typing while the right hand margin adjust system is deleting characters or is looking ahead to the hot zone to precondition the system for operation as determined by the characters in the hot zone. Under normal situations the hold for delete flip flop 41 will not be utilized because the operating time of the system is substantially faster than the reaction time of the typewriter.

The hold for delete flip flop 40 is conditioned on input pin 2, or the D input of the flip flop 40, by the special characters to be deleted, each of which constitutes an input to negative input NOR gate 656, described more fully below. The output of that NOR gate 656 on pin 8 is connected with lines 658 and 659 to input pin D of the hold for delete flip flop. The flop 656 is clocked by phase 7 of the 8 phase clock which is connected to the C input of the flip flop 656 along lines 660 and 661 to input pin 3. After the flop 656 has been clocked the lower output on output pin 6 is connected with line 663 to a negative input NOR gate 665 the output of which is connected with line 667 to input pin 13 of a NAND gate 670.

The second input to NAND gate 670 is connected to the phase 5 clock pulse along line 673 to the output of NAND gate 675. Therefore on phase 5 of the clock the output of pin 11 of NAND gate 670 will go low which is connected to output line 676 to hold the read clock.

This allows a read circuit (not shown) to check for recognition codes.

The read clock is also held by the output of the hold for insert flip flop 41. The hold for insert flip flop 41 is conditioned on input pin 12, or the D input, from the output of NOR gate 680 connected to the flip flop 41 by line 681. The input to NOR gate 680, on pin 5, is the space command indicating that one or more spaces should be inserted in the typed copy and on the tape to replace a deleted carrier return. This signal is connected to input pin 5 of the NOR gate 680 along lines 682 and 684 from the output of a NAND gate 686, pin 6. The input to NAND gate 686 is the space command signal, which is connected from input line 688 through inverter 690 and lines 691 and 692 to input pin 4 of the NAND gate 686.

The second enabling input to negative input NAND gate 686 is a signal indicating that a signal carrier return has been detected which therefore must be replaced by one or more spaces. The fact that one carrier return is loaded into the shift register 100 is connected from the QA output of the shift register 100, pin 15, to input pin 4 of a NAND gate 692 along lines 694, 695 and 696. The high signal indicating that the carrier return enable flop 33 has not be set is connected from output pin 14 along lines 698, 700 and 701 to input pin 5 of NAND gate 692. The fact that the character currently in the buffer is not a carrier return is connected from the carrier return input line 410, along lines 435, 436 and 704 to pin 3 of NAND gate 692. The resulting low output fully enables NAND gate 686 to condition the hold for insert flip flop 41 through NOR gate 680 and partially enables NAND gates 707 and 709 so that the space or spaces may be inserted on output line 710 and to clear the carrier shift register 100 on input pin 1. Additional gates, discussed more fully below, partially indicating that the next character is not kept, are provided to insert the space and clear the carrier return shift register 100 on the phase six clock pulse. These are inverter 712, NAND gate 716 and NAND gate 720 which fully enable NAND gate 709 to clear the carrier return shift register through NOR gate 724 and insert spaces through NAND gate 707 which is fully enabled on the phase six clock pulse when the signal on NAND gate 686 is high.

The second input to NOR gate 680 is the carrier return insert signal discussed above. This is connected from the output of inverter 489 along lines 728, and 730 to input pin 6 of NOR gate 680. The hold for insert flip flop 41 is clocked on phase 6 of the 8 phase clock which is connected from input line 552 along lines 554, 732 and 733, through NOR gate 538 and along lines 540 and 735 to input pin 11 of the hold for insert flip flop 41. In addition to holding the read clock on line 676 and providing the signal to insert the appropriate character on line 737 the hold for insert flip flop 41 also conditions a second flip flop 654 which upon a clocking impulse from the typing system, designated "load strobe", to input pin 3 of the flop 654 initiates the edit run signal from output pin 5 of the flop along line 739 through NOR gate 742 to the output signal designated "edit run". Thus, after a load strobe has been received from the typing system indicating that the applicable characters have been inserted the printing mechanism is again ready to accept additional printing commands. The system is returned to operating condition wherein the clock is operating so addi-

tional characters may be checked, for the purpose of editing or adjusting the right hand margin.

Other conditions which initiate edit run for the purpose of checking the additional characters and also which set the hold for delete flip flop 40 while the right hand margin adjust feature is checking additional characters to make the determination of whether or not spaces, carrier returns or the like will be deleted, are connected to a negative input NOR gate 656. For example, if a carrier return is detected it will either be deleted and replaced with a space if in the body of the text or it will be executed if it is followed by one or two additional carrier returns indicating the start of a new paragraph. Therefore upon the initial detection of a carrier return the hold for delete flip flop 40 will be conditioned and clocked and the edit run sequence will be initiated to determine whether or not the carrier return is followed by additional carrier returns. This is accomplished through NOR gate 656.

The input to input pin 12 of negative input NOR gate 656 is the carrier return loaded signal from the carrier return shift register 100 which is obtained from the QA output on output pin 15 and connected with line 103 to NAND gate 750, the low output of which is connected with line 752 to NOR gate 656. The other enabling signals to NAND gate 750 are the detected carrier return signal from the output of inverter 400 which is connected with lines 442, 443 and 446 to input pin 13 of NAND gate 750 and the carrier return NOR enabled signal which is connected from the output of the carrier return enable flip flop output pin 14 along lines 698, 700 and 754 to input pin 2 of NAND gate 750.

The input on pin 9 of NOR gate 656 indicates that there is not a carrier return nor an alphanumeric character in the read buffer. Initiation of this signal runs the clock ahead to get rid of unwanted spaces and the like up to the point that either an alphanumeric character or another carrier return is detected, after a carrier return has been inserted. The carrier return or alphanumeric characters are detected on input lines 410 and 425 through negative input NOR gate 428, input pins 1 and 2 respectively. The output on pin 3 is connected with lines 486 and 756 to input pin 9 of negative input NAND gate 430, the other enabling input being from the print character flip flop 30 and the zone memory shift register 270 indicating that there are one or more editable characters in the zone. These inputs are connected to input pin 8 of negative input NAND gate 430 through NAND gate 499.

The output of negative input NAND gate 430, pin 10, is connected with lines 497 and 758 to input pin 3 of NOR gate 760 which is connected with line 762 to input pin 9 of the four input negative input NOR gate 656. Similarly, the space command is connected to the second input of NOR gate 760 through negative input NAND gate 764 in conjunction with the hold for insert flip flop 41 the low output of which on pin 8 is connected with line 766 to the second input of NAND gate 764, input pin 9.

Connected to pin 13 of the negative input NOR gate 656 is an indication that the carrier return shift register 100 is not full and thus the typing is not at the end of a paragraph. Additional inputs also indicate that the character being interrogated is not an alphanumeric character, characterized by a data bit 7, that the keep key has not been depressed, and that a tab is the character being interrogated. Consequently, as explained

above, the tab is deleted and the circuitry is stopped so that the operator can reset the tab.

These signals are connected to input pin 13 through NAND gate 770 with line 768. The three input signals to NAND gate 770 are the tab signal on input line 630 connected through inverter 632 to input pin 10. The signal indicating that neither a keep key nor an alphanumeric character has been interrogated is connected to input pin 11 from input line 423 along lines 470 and 774 and the carrier return signal from the output of the carrier return enable flip flop 33 pin 14, along lines 698, 700, 754 and 780 to input pin 9 of NAND gate 770. The typing system is stopped with the circuitry shown in FIG. 1, particularly the zone stop flip flop 370.

The last situation which initiates edit run to check following characters is the input to pin 10 which is initiated by the occurrence of a hyphen which sets the hyphen flag 76. This signal is connected from input line 480 to input pin 10. As explained above, if the hyphen is followed by an alphanumeric character and is not a kept hyphen it is deleted.

The hyphen flag signal is also connected along the same line 480 to the input of positive input NAND gate 452 which functions to shift the carrier return shift register 100 to indicate the occurrence of a carrier return. NAND gate 452 is fully enabled if the hyphen flag signal is high, indicating that there is not a hyphen flag, and the carrier return enable flip flop 33 set, which is indicated on input pin 1 from the output of the carrier return flip flop 33 along lines 698, 700, 754 and 783, that a carrier return signal has been detected, which is connected to pin 5 from output of inverter 440 along lines 442, 443, 446 and 447, and the keep key has not been depressed, that signal being on input line 425 and connected to input pin 2 of NAND gate 452 along lines 470, 471 and 472. Therefore, in the event all four inputs to the NAND gate are enabled it indicates that a carrier return has been detected which is not followed by a hyphen nor is the carrier return to be kept. The output of NAND gate 452 is connected with line 788 to input pin 5 of negative input NOR gate 520 which shifts the carrier return shift register 100 one register to the right to delete the carrier return.

The additional inputs to NAND gate 750, which as explained above initiates edit run through NOR gates 656 and 790, is an indication that a carrier return has been loaded, obtained from the carrier return shift register 100, QA output, pin 15, which is connected to input pin 13 of NAND gate 750 with line 103, and the carrier return flip flop 33 output on pin 2. When all three of these signals are high they fully enable the NAND gate 750 and the carrier return is executed even though it is only one carrier return because it was the end of the typing in the initial format.

The QA indication indicating that a carrier return is loaded is also connected to NAND gate 563, input 11 which is ANDed with the end of page signal on input line 560 to execute any remaining carrier returns after the end of the page.

Finally, the QA indication is also connected to NAND gate 692 pin 4. The input to pin 5 of the NAND gate 692 indicates that a carrier return is not enabled from the output of the carrier return flip flop, output pin 14, and lines 698, 700 and 701. Therefore, the output on pin 6 will go low which, if the space command is high on input pin 4 of NAND gate 686, will make the

output of negative input NAND gate 686 low. The low output on pin 6 of NAND gate 692 is also inverted with inverter 712 and connected to input pin 3 of NAND gate 716. This is connected to NAND gate 720 from output pin 6 to input pin 12. The second enabling input to NAND gate 2A is the phase 6 clock pulse which is connected to input pin 13 from the phase 6 clock input line 552 along line 794. That output, on pin 11, fully enables the negative input NAND gate 709 which creates a space. That output clears the carrier return counter and a space is inserted. The space is inserted due to NAND gate 707 which is also partially enabled by the phase 6 clock pulse from input line 552 along lines 554, 732 and 796 to input pin 4 and fully enabled by the second input originating from pin 6 of negative input NAND gate 686 along lines 682 and 683 to input pin 5.

Finally, the output of pin 6 of negative input NAND gate 686 also conditions the hold for insert flip flop 41 along lines 682, 683, 684, NOR gate 680 and line 681 to the D input, pin 12 of the hold for insert flip flop.

After the space command, input pin 5 of NAND gate 716 will go high and pins 3 and 4 will be high. Therefore, pin 6 will go low which is connected with lines 798 and 799 to input pin 12 of negative input NOR gate 800 the output of the NOR gate is connected to an inverter 802 along line 805. The output of the inverter 802 is connected with line 804 to negative input NAND gate 764 which is fully enabled by the low output of the hold for insert flip flop 41 along line 766. The output of negative input NAND gate 764 is connected with line 807 to input pin 2 of NOR gate 760 the output of which, is connected with line 762 to input pin 9 of negative input NOR gate 656 which initiates an edit run output to look ahead for the next character.

In the manner described above the body and the hot zone prior to the right hand margin are sequentially interrogated and adjusted to reformat the original material in accordance with the objectives of the invention as exemplified by the sequence sheets first described.

To fully indicate the sequential operation of the circuitry, reference may be had to the flow sheet designated FIG. 3. The marginal references are to be controlling parameter or signals from FIGS. 1 and 2. The following typing pattern will be traced and it should be obvious that any of the sequences listed on the sequence sheet or any other chosen sequence may be similarly traced. In the examples the marks indicate the sixth character hot zone and an asterisk represents a carrier return.

For purposes of illustration assume that the Pledge of Allegiance is originally typed and recorded with margin settings of 15 on the left and 85 on the right. This would appear as follows:

I pledge allegiance to the flag of the United States of America and*
to the republic for which it stands, one nation, under God, indiv-* isible, with liberty and justice for all.**

If, thereafter, the right margin was changed from 85 to 75 and the tape was retyped, with the adjust feature energized, the right margin for the first sentence would then end after the sixtieth character in the line, or after the letter *i* in America and the hot zone prior to the right hand margin would begin after the letter *f* in the second occurrence of the word "of" in the first sentence of the Pledge.

Referring now to FIG. 3, the first letter in the read buffer would be the letter I. The adjust feature would be on. An end of page code would not be detected. A stop code would not be detected. A tab would not be detected. A line return would not be detected. The system would not be operating in the zone. A hyphen would not be detected. The hyphen flag would therefore not be set. A kept hyphen would be detected. A sentence ending punctuation mark would not be detected. A space kept space would not be detected. The carrier return counter would not be full. A kept carrier return would not be detected. A kept tab would not be detected. A carrier return would not be detected. The typing would not be in the zone. The carrier return counter would be empty and thus the system would print the letter I and bring the next typing character into the read buffer decoder position which would be the space. The spacer counter would equal zero. The adjust stop would not be set. Therefore, more tape would be read into the 200 character buffer if needed and the cycle would continue.

The adjust would be on. An end of page code would not be detected. A stop code would not be detected. A tab would not be detected. A line return would not be detected. The zone switch would not be detected. A hyphen would not be detected. A kept hyphen would not be detected. Sentence ending punctuation would not be detected. A space would be detected. Therefore, the space counter would be incremented by one to indicate one space in the space counter, that space would be printed and the next character would be entered in the read buffer which would be the letter p. The adjust stop would not be set and, thus, more tape would be read into the 200 character buffer if necessary and the cycle would continue.

This cycle would continue throughout the typing in the first line of the Pledge until the zone switch is made after the letter f in the second occurrence of the word of. The first character after the letter f is a space. Therefore, the adjust would be on. An end of page code would be not detected. A stop code would not be detected. A tab would not be detected. A line return would not be detected. Entry into the zone would be detected. Therefore, the read recirculate control flip flop, 171 on FIG. 1, would be set. The end of the zone would not be detected. A space which is not kept would be detected. Thus, the margin counter insert memory shift register 270 in FIG. 1, would be incremented by one, the insert flag, hold for insert flip flop 41 in FIG. 2, would be set and the read clock 1 signal would go high. The zone recycling counter would be incremented by one and the 200 character buffer would be shifted one. The next character, being the letter A in America, would be brought to the read buffer decoder position. The end of the buffer would not be detected. The end of the zone would not be detected. The letter A is neither a space which is not kept nor a carrier return nor a carrier return which is kept. Thus, the zone counter would again be incremented and the 200 character buffer would be shifted and the letter m would be brought to the read buffer decoder position. This would continue until the end of the zone is detected after the letter i in America.

When the end of the zone is detected, the read buffer would be recirculated for the balance of the 200 characters so that the space would again be in the read

buffer decoder position. The margin counter would not equal zero because of the first space which was detected. A space would be in the read buffer decoder position, therefore, one would be subtracted from the margin counter on phase 6 of the clock. A neither a carrier return nor kept carrier return would be detected. The margin counter would now equal zero. Neither a carrier return nor a kept carrier return would be detected. A 7 bit, indicating an alphanumeric character, would not be detected, nor any indication that the keep key was depressed. Therefore, the next character, the letter A in America, would again be brought to the read buffer decoder position. More tape would be entered into the 200 character buffer if necessary. The letter A is not a carrier return nor a kept carrier return. The letter A is an alphanumeric character indicated by the read buffer 7 data bit. Therefore, the carrier return counter would be loaded with one carrier return if the Pledge is being typed in a normal typing style or two carrier returns if the Pledge is being typed in a legal typing style. The carrier return enable flip flop 33 in FIG. 2, would be set on phase 5 of the eight phase clock. The carrier returns would be executed on phase 6 of the eight phase clock. The zone flop and adjust stop flip flops would be cleared. Since the letter A would still be in the read buffer decoder position neither a carrier return nor a kept carrier return nor a kept tab would be detected. Therefore, the carrier return flag would be cleared. The adjust stop would not be set. More tape would be read into the 200 character buffer, if required, and with the letter A still in the read buffer decoder position the system would initiate editing the second line of the Pledge beginning with the word America.

The second line would proceed from the word America in the same manner as described above until the letter d, the last letter in the word and, is in the read buffer. Starting from the start position, the carrier return would be deleted and replaced by one interword space in the following manner.

The adjust would be on. An end of page code would not be detected. A stop code would not be detected. A tab would not be detected. A line return would not be detected. The typing system would not be operating in the zone. A hyphen would not be detected. The hyphen flag would not be set. A keep hyphen would not be detected. Sentence ending punctuation would not be detected. A space or a kept space would not be detected. The carrier return counter would not be full. A kept carrier return would not be detected. A kept tab would not be detected. A carrier return would not be detected. The system would not be operating in the zone. The carrier return counter would be empty. Therefore, the letter d would be printed and the carrier return would be brought to the read buffer decoder position. The space counter would equal zero. The adjust stop flip flop would not be set. Therefore, more tape would be read if necessary and the cycle would begin again.

The adjust feature would be energized. An end of page code would not be detected. A stop code would not be detected. A tab would not be detected. A line return would not be detected. The system would not be operating in the zone. A hyphen would not be detected. The hyphen flag would not be detected. A kept hyphen would not be detected. Punctuation would not be detected. A space or kept space would not be detected. The carrier return counter would not be full. A kept

carrier return would not be detected. A kept tab would not be detected. A carrier return would be detected. Therefore, the carrier return counter would be incremented by one on phase 6 of the eight phase clock. More tape would be read if necessary and the next character which would be the letter *t* in the word to would be brought to the read buffer decoder position on the phase 1 clock pulse. Thereafter, the carrier return counter would not be full. A kept carrier return would not be detected. A kept tab would not be detected. A carrier return would not be detected. The system would not be operating in the zone. The carrier return counter would not be empty. A punctuation flag would not be detected. The space counter would equal zero. Therefore, a space would be generated on phase 15 6 of the eight phase clock. The system would not be operating in the zone. A digit 7, indicating an alphanumeric character would be detected due to the letter *t* which would be presently in the read buffer decoder position. Therefore, the carrier return counter would be cleared on phase 6 of the eight phase clock. The space counter would also be cleared on phase 6 of the 200 clock and the punctuation flag would be cleared on phase 5 of the clock. The adjust stop flip flop would not be set. More tape would be obtained to fill the character buffer if necessary and the system would continue to reproduce the second line of the Pledge until the zone switch is energized which would occur after the letter *a* and prior to the letter *t* in nation. In the manner described above for the first sentence, the space following the comma following the word nation would be utilized for a carrier return and the space would be deleted.

The third line of the reformed copy would then begin with the word under and the system would operate as described above until the *v* in individual would be present in the read buffer decoder position. Referring to FIG. 3, at the start of the sequence the adjust feature would be energized. An end of page code would not be detected. A stop code would not be detected. A tab would not be detected. A line return would not be detected. The system would not be operating in the zone. A hyphen would not be detected. Sentence ending punctuation would not be detected. A space or a kept space would not be detected. The carrier return counter would not be full. A kept carrier return would not be detected. A kept tab would not be detected. A carrier return would not be detected. The system would not be operating in the zone. The carrier return counter would be empty. Therefore, the letter *v* would be printed and the hyphen would be brought to the read buffer decoder position. The space counter would equal zero and the adjust stop flop would not be set. Therefore, more tape would be read, if necessary, and the sequence would begin to edit the hyphen.

The adjust feature would be energized. An end of page code would not be detected. A stop code would not be detected. A tab would not be detected. A line return would not be detected. A zone would not be detected. The hyphen would be detected. Therefore, the hyphen flag would be set on phase 5 of the clock. The hyphen flag would be detected. Therefore the carrier return would be brought to the read buffer decoder position on phase 1 of the clock. More tape would be read if necessary. The carrier return would not be a kept carrier return nor would it be an alphanumeric character which is not a hyphen. Therefore, the next character

5 ter, which would be the letter *i*, would be brought to the read buffer decoder position on phase 1 of the clock. More tape would be read if necessary. An alphanumeric character which is not a hyphen would be detected and therefore, the hyphen flag would be cleared on phase 5 of the clock. With the letter *i* still in the read buffer decoder position the sequence would continue. A keep hyphen would not be detected. Punctuation would not be detected. A space or a kept space would not be detected. The carrier return counter would not be full. A kept carrier return would not be detected. A kept tab would not be detected. A carrier return would not be detected. The system would not be operating in the zone. The carrier return counter would be empty. Therefore, the letter *i* would be printed and the next letter, the letter *s*, would be brought to the read buffer decoder position on the first phase of the clock. The space counter would continue to equal zero. The adjust stop would not be set. Therefore, the third line of the Pledge would be continued in the manner described above and both the hyphen and the carrier return would have been deleted in the retyped copy.

The third line would be continued until the zone margin switch would be energized which would occur between the letters *l* of the word all. With the last letter *l* in the read buffer decoder position, which would be in the first position of the zone, the system would operate as follows. The adjust feature would be energized. 25 An end of page code would not be detected. A stop code would not be detected. A tab would not be detected. A line return would not be detected. The system would be operating in the zone. Therefore, the read recirculate signal would be set. The end of the zone would not be detected. The letter *l* would not be a space which is not kept nor a carrier return nor a kept carrier return. Therefore, the zone counter would be incremented as well as the 200 character buffer. The next character would be brought to the read buffer 30 code position which would be the period.

The end of the buffer would not be detected. The end of the zone would not be detected. The period would not be a space which is not kept nor a carrier return nor a kept carrier return. The zone counter would be incremented again as well as the 200 character read buffer. The first carrier return would be brought to the read buffer decoder position.

The end of the buffer would not be detected. The end of the zone would not be detected. The carrier return 45 would be detected. Thus, the margin counter would be incremented by 1 and the insert flag would be set. The zone counter and the 200 character buffer would both be incremented by one and the second carrier return would be brought to the read buffer decoder position.

The end of the buffer would not be detected. The end of the zone would not be detected. The second carrier return would be detected and thus the margin counter would again be incremented by one. The zone counter and the 200 read buffer would also be incremented by one, to bring either an end of page code or a stop code to the read buffer decoder position if these were initially indicated by the operator who recorded the Pledge with the wide margins. If not, a recognition code would be present signaling the end of the buffer. In either of these events, the end of the buffer would be detected and the 200 character buffer would be recirculated to the beginning of the zone or to where the last

/ in the word all is present in the read buffer code position.

The margin counter would equal 2 and therefore would not equal zero. The letter / would not be a space nor a carrier return nor a kept carrier return. A tab 5 would not be detected. Therefore, the letter / would be printed and the period would be brought to the read buffer decoder position. A period would not be a space or a carrier return or a kept carrier return. There would not be a tab, therefore, the period would be printed and the first carrier return would be brought to the read 10 buffer decoder position. The carrier return would be detected and thus one would be subtracted from the margin counter on phase 6 of the clock. The carrier return would be detected and, therefore, the zone insert 15 enable would be cleared on phase 7 of the clock. The carrier return counter would not be full. A kept carrier return would not be detected. A tab would not be detected. A carrier return would be detected, thus the carrier return counter would be incremented by one on 20 phase 6 of the eight phase clock. More tape would be read into the 200 character buffer if necessary. The second carrier return would be brought to the read buffer decoder position on phase 1 of the clock.

The carrier return counter would not be full. The 25 kept carrier return would not be detected. A kept tab would not be detected. The second carrier return would be detected. Thus the carrier return counter would be incremented to two on phase 6 of the clock. More tape would be read if necessary and the next 30 character code would be brought to the read buffer decoder position on phase 1 of the clock, which would be the end of page code stop code or a recognition code as explained above.

The carrier return counter would now be full, therefore the carrier return enable would be set on phase 5 of the clock. Two carrier returns, or three, if legal typing style is chosen, would be executed on phase 6 of the clock. The zone flip flop and the adjust stop flip flop would be cleared. Neither a carrier return or a kept 40 carrier return nor a kept tab would be detected. The carrier return flag would be cleared, the adjust stop flip flop would not be set and, therefore, the sequence would end with the end of page or stop code signals if indicated. Alternatively, if typing continued, the first 45 letter in the next paragraph would be processed in the sequence and manner described above. Thereafter the reformed copy, as typed and recorded, would appear as follows:

.....
I pledge allegiance to the flag of the United States of*
America and to the republic for which it stands, one na-
tion,*
under God, indivisible, with liberty and justice for
all.**
.....

In general, while we have described a specific embodiment of our invention, it is to be understood that this is for the purposes of illustration only and that many various modifications can be made within the 60 scope of the invention and that all such modifications are within the intentment of our invention.

We claim as our invention:

1. In an automated printing system of the type having:
information storage means containing coded character print commands which are to be reprinted in

lines of characters having a different number of characters per line than originally recorded; input means for recording the coded character print commands on the information storage means; reading means to read the print commands from the information storage means; and printing means for reproducing character print commands stored on the information storage means the improvement comprising, in combination:

means for establishing a multiple character zone prior to the end of each line of characters to be reprinted;

means for detecting selected special character print commands read by the reading means;

means for distinguishing special characters which are to be printed in the multiple character zone from characters which are to be printed prior to the multiple character zone comprising

means to detect the beginning of the multiple character zone;

first logic means responsive to the means for distinguishing characters to be printed in the zone from characters to be printed prior to the zone for selectively executing prior to the multiple character zone certain of the print commands and for generating and executing other character print commands that are different than those originally recorded; and

second logic means responsive to the means for detecting the beginning of the multiple character zone for sequentially interrogating and analyzing a number of character print commands equal to the number of characters in the multiple character zone immediately prior to executing any character print commands to be printed in the multiple character zone, the second logic means being operatively connected to the first logic means so that the character print commands which are selectively executed and those which are generated and executed in the multiple character zone are determined by the second logic means whereby the information originally recorded can be printed in lines of characters which have a different number of characters per line than originally recorded.

2. The improvement of claim 1 further comprising means for detecting the end of the multiple character zone.

3. The improvement of claim 1 wherein the means for detecting selected special character print commands comprises means for detecting sentence-ending punctuation print commands.

4. The improvement of claim 1 wherein the means for detecting selected special character print commands comprises means for detecting hyphen print commands.

5. The improvement of claim 1 wherein the means for detecting selected special character print commands comprises means for detecting space print commands.

6. The improvement of claim 5 further comprising means for registering the number of space print commands detected by the second logic means and wherein if one or more space print commands are detected in the multiple character zone the last occurring space print command is not executed and one or more carrier return print commands are generated and executed by the first logic means.

7. The improvement of claim 1 wherein the means for detecting selected special character print commands comprises means for detecting carrier return print commands.

8. The improvement of claim 7 further comprising means for detecting the beginning of a new paragraph in the coded character print commands recorded on the information storage means wherein if a carrier return print command is detected which does not occur in the multiple character zone and which is not the beginning of a new paragraph the carrier return print command is not executed and one or more space print commands are generated and executed by the first logic means.

9. The improvement of claim 8 wherein the means for detecting selected special characters further comprises means for detecting sentence-ending punctuation print commands wherein if a carrier return print command is detected immediately following the detection of a sentence-ending punctuation print command which is not the beginning of a new paragraph and which does not occur within the multiple character zone the carrier return print command is not executed and two space print commands are generated and executed by the first logic means.

10. The improvement of claim 1 wherein the means for detecting selected special character print commands comprises means for detecting tab print commands.

11. The improvement of claim 10 further comprising inhibiting means responsive to the means for detecting tab print commands and operatively connected to the first logic means for inhibiting the first logic means from executing or generating any print commands if a tab print command is detected by the means for detecting tab print commands.

12. The improvement of claim 1 wherein the means for detecting selected special character print commands comprises means for detecting line return print commands.

13. The improvement of claim 12 further comprising inhibiting means responsive to the means for detecting line return print commands and operatively connected to the first logic means for inhibiting the logic means from executing or generating print commands if a line return print command is detected by the means for detecting line return print commands.

14. The improvement of claim 1 wherein the improvement further comprises a keep key operatively connected to the input means for recording a keep key code and keep key code detection means operatively connected to the first logic means and the second logic means for preventing the first logic means and the second logic means from selectively executing or generating and executing any of the selected special characters which are detected in conjunction with the keep key code detection means whereby any selected special character print command detected in conjunction with a keep key code is executed as originally recorded.

15. The improvement of claim 1 wherein the means

for detecting selected special character print commands comprises means for detecting space print commands and means for detecting carrier return print commands and wherein the second logic means comprises means for registering the number of space unit commands and carrier return print commands which are detected by the second logic means and wherein the second logic means comprises means for causing a carrier return print command to be executed if it is detected in the multiple character zone or for causing a carrier return print command to be generated and executed and the last detected space print command not to be executed if one or more space print commands are detected but no carrier return print commands are detected by the second logic means.

16. The improvement of claim 1 wherein the reading means comprises memory means for storing the information read from the information storage means and wherein the second logic means comprises recirculating means connected to the memory means for recirculating the information in the memory means so that after the first interrogation of each of the characters in the multiple character zone by the second logic means each character print command is again interrogated by the reading means prior to printing and the character print commands are executed by the first logic means in accordance with logic of the second logic means.

17. The improvement of claim 1 further comprising clocking means for establishing a multiple phase clock and wherein the character print commands recorded on the information storage means are read, detected, and selectively executed, or generated and executed sequentially on different phases of the multiple phase clock by the first and second logic means.

18. The improvement of claim 17 further comprising means for controlling the operation of the clocking means including means for inhibiting the clocking means when special selected characters are being executed or generated and executed by the first logic means.

19. The improvement of claim 1 wherein the means for detecting selected special character print commands comprises means for detecting space print commands and means for detecting carrier return print commands and further comprising means for inhibiting the printing means if no space print commands or carrier return print commands are detected by the second logic means in the character print commands to be printed in the multiple character zone.

20. The improvement of claim 1 further comprising switching means having two positions for varying the printing style of the information reproduced by the printing means wherein one or more carrier return print commands are executed or generated and executed to produce a normal printing style if the switching means is in one position and two or more carrier return point commands are executed or generated and executed to produce a legal printing style if the switching means is in a second position.
